UNITED STATES PATENT OFFICE.

OTTO CARL SOBOLEWSKI, OF CINCINNATI, OHIO, ASSIGNOR OF ONE-HALF
TO GEORGE SUCKART, OF SAME PLACE.

CLOTHES-RACK.

SPECIFICATION forming part of Letters Patent No. 461,964, dated October 27, 1891.

Application filed February 3, 1891. Serial No. 379,983. (No model.)

To all whom it may concern:

Be it known that I, OTTO CARL SOBOLEWSKI, a citizen of the United States, residing at Cincinnati, in the county of Hamilton and State 5 of Ohio, have invented certain new and useful Improvements in Combined Hat-Racks and Clothes-Racks, of which the following is a full, clear, and exact description, reference being had to the accompanying drawings, forming 10 part of this specification.

My invention relates to that class of portable racks which are simply and readily convertible from a hat-rack to a clothes-drier, and vice versa; and it has for its object the improved 15 construction of such racks.

The novelty of my invention will be hereinafter set forth, and specifically pointed out in the claim.

In the accompanying drawings, Figure 1 is 20 an elevation of my improved rack arranged as a hat-rack. Fig. 2 is a sectional detail of the upper part of the same, with the arms supported horizontally for a clothes-drier. Fig. 3 is a plan view of the upper supporting- 25 disk. Fig. 4 is a detail sectional view of one of the arms in a modified form. Fig. 5 is a detail view of the umbrella-supporting hooks.

The same letters of reference are used to indicate identical parts in all the figures.

30 A is a metal base-piece, having a suitable number of supporting-feet *a* and upon its upper side a central annular groove *b*, dotted lines, Fig. 1. The said groove forms a drip-cup for umbrellas. Secured to and extending 35 up centrally from the base A is a vertical metal standard B, round in cross-section, and preferably tubular to combine lightness with strength. Upon the upper end of the standard B is centrally fitted a circular metal disk 40 C, having projecting from its periphery a number of fingers or hooks *c*, upon which to hang coats. The periphery of the disk is a downturned flange *d*, Fig. 2, between which and the center there is a concentric upwardly- 45 curved annular portion *e* to form a semicircular annular groove on the under side of the disk. There are a number of equidistant perforations *f*, Fig. 3, through the disk between its periphery and the raised portion *e*, 50 and coincident with these perforations are grooves *g* in the flange of the periphery.

The disk C is revolute upon the standard B, and is supported by a collar D, adjustable upon the standard and held in place by a set-screw *h*.

Beneath the disk C, upon the standard B, is a second saucer-shaped disk E, revolute upon the standard and supported by a collar F, with set-screw *i*, so as to be adjustable. The disk E may be provided on its periphery 60 with fingers or hooks *j*, Fig. 1, upon which to hang articles.

Inserted through the perforations *f* in the disk C are a number of supporting-arms G, of wood or metal and with knobs upon both 65 ends. The knobs of the lower ends rest and are confined in the upper part of the disk E, as shown in Fig. 1, when the rack is to be used for a hat-rack, the hats being placed on the upper ends of the arms. When it is desired to use the rack as a clothes-drier, the arms G are lifted and drawn out horizontally until their lower knobs rest in the groove under the portion *e* of the disk C, as shown in Fig. 2. As shown in Fig. 4, the arms may be 75 tubular and in two parts, the upper one G' confined and sliding within the lower one, so as to make the arms extensible. By means of the lower adjustable supporting-disk E the arms G may be given any inclination desired. 80

Beneath the disk E, upon the standard, is secured a collar carrying horizontal hooks H, to serve as supports for umbrellas, whose lower ends rest in the grooves *b* in the base A.

Upon the upper end of a standard a lamp 85 or any ornamental piece may be fitted, as illustrated in Fig. 1.

Having thus fully described my invention, I claim—

The combination, with a base A and standard B, of the disks C and E, revolute on said standard, the former having the apertures or perforations *f*, and the latter being saucer-shaped, as shown, and the arms G inserted in said apertures and having heads at 90 their lower or inner ends, said arms being made in two parts, one sliding within the other.

OTTO CARL SOBOLEWSKI.
